UNITED STATES PATENT OFFICE.

JOHN E. PRACNY, OF WATERBURY, CONNECTICUT, ASSIGNOR TO THE E. J. MANVILLE MACHINE COMPANY, OF WATERBURY, CONNECTICUT, A CORPORATION OF CONNECTICUT.

PUNCH HOLDER FOR DOUBLE-BLOW HEADING MACHINES.

Application filed August 15, 1927. Serial No. 212,984.

This invention relates to those machines for heading cold metal stock, such as slugs cut from wire or rod, having two punches, each of which acts upon the stock during 5 each cycle of the machine operations. In such machines the punches are arranged one above the other so as to reciprocate longitudinally and also to move transversely and be alternately brought into line with the die 10 for acting upon the stock. To accomplish this the punches are mounted on a slide that by suitable mechanism is given a vertical movement in the end of a gate which by suitable mechanism is given a horizontal 15 reciprocation, the operating mechanisms being timed so that during the return reciprocatory movements of the gate and punches the position of the slide is changed and the elevations of the punches altered to bring 20 first one into line with the die and then the other into line with the die. The vertically movable slide, of course, must have a working fit in the end of the gate, that is, a fit with sufficient clearance to permit it to slide 25 up and down freely, and there is a considerable distance between the back of this slide and the faces of the punches. Frequently the end of the stock is not cut off square or smooth so as to be parallel with 30 the faces of the punches, in which case there is resistance which tends to force the punches sidewise as they strike the stock. Such an action causes sidewise strain on the slide which results in excess friction and undue 35 wear on the slide and the ways in which it moves, besides resulting in an imperfect product.

The object of this invention is to so construct the punch supporting parts of a cold 40 heading machine which is designed to act rapidly and strike two blows upon a piece of stock, that the sidewise effect or whipping action of the vertical movable slide is practically eliminated, whereby the moving parts 45 will operate more freely, have a longer life and produce a more uniformly perfect product than the prior headers of this type.

In the embodiment of the invention illustrated this object is attained by fastening a 50 hardened plate between the front face of the vertically movable slide and the punch holder block, and extending this plate to one side and fitting its projecting edge into a guideway formed between the front end of the

gate and a gib that is fastened to the gate, 55 thus providing a guideway independent of the regular gate guideway which resists any tendency of the slide to whip under sidewise strains on the faces of the punches.

In the accompanying drawings Fig. 1 60 shows a vertical section of the gate, slide, punch holder and so much of the mechanism for reciprocating the gate and raising and lowering the slide of a well known double blow solid die cold heading machine, as is 65 necessary to an understanding of the present invention. Fig. 2 is a plan of the parts shown in Fig. 1. Fig. 3 is, on larger scale, 70 a front elevation of the slide and punches and the means for raising and lowering the slide. Fig. 4 is a plan of the parts shown in Fig. 3.

The gate 1 is reciprocated longitudinally in ways in the frame 2 by the crank 3 and crank rod 4 in the manner usual in machines 75 of this character. The transfer slide 5 is fitted in a dove-tail way 6 in the front end of the gate so as to be reciprocated horizontally therewith but have a free vertical movement, and it is raised and lowered at the 80 proper times by the action of the rocker 7 operating as is well known in these machines. In front of the transfer slide is a hardened steel plate 8 and in front of this plate is the punch block 9, the punch block and plate being rigidly fastened to the slide by bolts 85 10. The punches 11 are fastened in the front ends of the punch block by suitable means, and as the gate is reciprocated the elevation 10 of the slide is effected so that first one punch and then the other punch will be brought 90 into line with the die 12 for acting upon the stock.

In carrying out the object of this invention the intermediate or hardened backing 95 plate 8 is extended to one side for practically its entire length providing a wing 13, and the end of the gate is provided with a forward extension 14. Fastened to this extension 14 is a gib 15, and the extended side 100 edge or wing of the plate has an operative fit in the opening provided by this extension of the gate and the gib. As a result of this construction the transfer slide, carrying the plate, punch block and punches, travels back 105 and forth horizontally with the gate and has a free vertical movement at the proper times, being retained in such a manner that

any tendency of the punches to slide side-
wise either way when they engage the stock
is resisted by the plate wing, and thus twisting
or binding of the transfer slide in its
5 way is rendered impossible.

The invention claimed is:—

1. In a machine for swaging cold metal stock, the combination with a horizontally movable gate and a slide carrying a plural-
10 ity of punches fitted into a way in the gate so as to travel horizontally with but have a vertical movement independent of the gate, of means extending to one side from the front face of the slide into a way at the end 15 of the gate for resisting sidewise strains on the slide incident to the action of the punches on the stock.
2. In a machine for swaging cold metal stock, the combination with a horizontally 20 movable gate and a slide carrying a plural- ity of punches fitted into a dovetailed way in the gate so as to travel horizontally with but have a vertical movement independent of the gate, of means extending to one side 25 from the slide into a way independent of the dovetailed way, at the end of the gate for resisting sidewise strains on the slide incident to the action of the punches on the stock.
3. In a machine for swaging cold metal stock, the combination with a horizontally 30 movable gate and a slide carrying a plural- ity of punches fitted into a way in the gate

so as to travel horizontally with but have a vertical movement independent of the gate, 35 of a plate attached to and extending sidewise beyond the slide into a way at the end of the gate for resisting sidewise strains on the slide incident to the action of the punches on the stock.

4. In a machine for swaging cold metal stock, the combination with a horizontally movable gate and a slide carrying a plural-
40 ity of punches, fitted into a way in the gate so as to travel horizontally with but have a vertical movement independent of the gate, of a plate attached to and extending side-
45 wise beyond the slide, and a gib attached to the gate and engaging the edge of the plate for resisting sidewise strains on the slide 50 incident to the action of the punches on the stock.

5. In a machine for swaging cold metal stock, the combination with a horizontally 55 movable gate, of a slide carrying a plate and a punch block adapted to hold a plural-
60 ity of punches, said slide being fitted into a dovetailed way in the gate so as to travel horizontally with but have a vertical move-
65 ment independent of the gate, said plate extending from one side of the slide into a way at the end of the gate and independ-
70 ent of said dovetailed way for resisting side-
75 wise strains on the slide incident to the ac-
80 tion of the punches on the stock.

JOHN E. PRACNY.
